ALARM DEVICE

Albin Jaeger, Brooklyn, N. Y.

Application April 21, 1932, Serial No. 606,625

2 Claims. (Cl. 177—311)

This invention relates to improvements in alarm devices, particularly to a device for sounding an alarm as soon as the water level in a bath tub rises above a certain predetermined level.

It is the principal object of my invention to provide such a device in which a float adjustable in vertical direction along a suitable guide member closes the alarm circuit as soon as the 10 float has reached a predetermined position controlled by the rising water level in a bath tub to audibly announce this fact, thus calling the attention of the attendant to the fact that the water supply should be shut off.

15 Another object of my invention is the provision of an alarm device for bath tubs which can readily be attached to the wall of a bathroom and which is made in two parts hinged together to allow a folding of the device out of 20 the way of a person taking a bath.

A further object of my invention is the provision of an alarm device of comparatively simple and inexpensive construction yet durable and efficient in operation.

25 A still further object of my invention is the provision of an alarm device announcing the impending overflowing of a bath-tub in which circuit closers of novel and improved construction and arrangement are used.

30 These and other objects and advantages of my invention will become more fully known as the description thereof proceeds, and will then be specifically defined in the appended claims.

In the accompanying drawing forming a material part of this disclosure:

Fig. 1 is a perspective view of a bath tub equipped with an alarm device constructed according to my invention.

Fig. 2 is a side elevation of the alarm device 40 on a somewhat enlarged scale.

Fig. 3 is an end view of the same.

Fig. 4 is a section on line 4—4 of Figure 2.

Fig. 5 is a top plan view of the hinge plate.

Fig. 6 is a section on line 6—6 of Figure 5.

45 Fig. 7 is a perspective view of the contact arrangement.

Fig. 8 is a bottom plan view of the battery and bell container with its cover plate removed.

As illustrated, my alarm device comprises a 50 block or elongated support 10 to which is hingedly connected, as at 11, and 11', a plate 12 the outer end of which carries an angular bracket

13 having one of its branches provided with openings allowing the passage of fastening means 14 55 for securing the device to the wall of a bath

room 15 just above the upper edge of the bath tub 16. From the front edge of support 10 are vertically depending the metal rods or bars 17 and 18 substantially parallel to each other and spaced from one another.

The rod 17 is preferably circular in cross-section while the rod 18 has a square cross-section and the outer ends of both rods 17 and 18 are connected by a plate 19 of insulating material.

A sleeve 20 having an axial aperture square in 10 cross-section to fit the square rod 18 is slidably guided on rod 18 and can be locked in any of its adjusted positions to rod 18 by means of a set screw 21.

A contact bar 22 having an angular contact 15 finger 23 at its inner end is pivotally attached as at 23' to a boss on sleeve 20 and carries at its outer end a float 24.

Metal bar 17 is connected by means of a conductor wire 25 guided properly insulated through 20 support 10 to a leaf spring contact 26, held spaced from the hinge 11 when the device is in inoperative or folded position. A metal plate 27 within plate 12 extends longitudinally therethrough. Rod or bar 18 is connected by a conductor wire 25 28 guided through support 10 properly insulated in a suitable manner, to a contact plate 29 forming part of the hinge 11' at the end of a metal plate 30 longitudinally extending in plate 12 through the same, but spaced from plate 27. 30

A box 31 having a removable cover is attached to the underside of plate 12, and within this box pole screws 32, 33, are provided to which the inner ends of metal plates 27, 30, are conductively connected.

35 Pole screws 32, 33, are held to one side of a cross bar 34 on plate 12 to the opposite side of which bar contact springs 35, 36, are secured in engagement with the poles of batteries 37, 38, composed of a plurality of coupled elements, the 40 other poles of which are connected by means of wires 39, 40, to the pole screws of an electric bell 41.

In use, the device is attached to the wall of a bath room just above the upper edge of a bath 45 tub and support 10 is turned about its hinges 11, 11' in alignment with plate 12.

The sleeve 20 is now locked to rod 18 at the proper height above the bottom of the bath tub by means of set screw 21 with the contact finger 50 23 of the float rod 22 out of engagement with rod 17.

If the swimmer 24 upon the rising of the water within the bath tub to a predetermined level, determined by the position of the sleeve, has as- 55

sumed an approximately horizontal position, it will engage finger 23 with rod 17 and thus a circuit will be closed over bell 41 which will sound the alarm.

5 It will be understood that I have described and shown the preferred form of my device as one example only of the many possible ways to practically construct the same, and that I may make such changes in its general arrangement and in 10 the construction of the minor details thereof, as come within the scope of the appended claims without departure from the spirit of my invention, and the principles involved.

Having thus described my invention, what I 15 claim as new and desire to secure by Letters Patent is:

1. An alarm device for audibly indicating the rise of the water level in a bathtub above a certain pre-determined point, comprising a support, 20 a plate hingedly connected with said support at two separate points, said support adapted to be folded upon said plate when the device is not in use, a pair of parallel metal rods depending from said support insulated from one another, one of 25 said rods being circular in cross section and the other non-circular in cross section, a sleeve having an opening of non-circular cross-section permitting it to slide on said rod having non-circular cross section and prevented from turning on 30 said rod, means for securing said sleeve on its rod in any of its adjusted positions, a source of current and an electric alarm and a circuit in which said metal rods and alarm are located, a

float having an arm of conducting material pivoted intermediate its ends on said sleeve to provide a contact finger normally held out of contact with the other of said rods, said finger engaging the rod of circular cross section as soon as the float arm assumes a substantially horizontal position on the water level to close the circuit and sound the alarm. 5

2. In an alarm device comprising a support, a pair of parallel metal rods depending from said support spaced from one another, one of said rods having a round, and the other a square cross-section, an insulating means connecting the lower end of said rods, a sleeve having an axial aperture square in cross-section to fit the square rod 15 and slideable thereon, a means to lock said sleeve to said rod at any desired point thereof, a boss on said sleeve, a pivot pin on said boss, an arm of conducting material pivoted to said pin intermediate its ends, a contact at the inner end of said arm, a float at the outer end of said arm for operating said contact, conductors connected to the ends of said rods, and a source of electricity to which the other ends of said conductors are connected, an alarm, and a circuit in which said 20 alarm, rods and source of electricity are located, said contact closing the alarm circuit upon its engagement with the rod having the round cross-section determined by the adjustment of said sleeve on its rod and the rise of the float on the 25 water level to a pre-determined point. 30

ALBIN JAEGER.
